Specification for Design.

Patented Feb. 29, 1916.

Application filed November 28, 1914. Serial No. 874,569. Term of patent 3½ years.

To all whom it may concern:

Be it known that I, GEORGE A. VAIPAN, a subject of the Austro-Hungarian Monarchy, and a resident of Windsor, in the county of Essex, Province of Ontario, and Dominion of Canada, have invented a new, original, and ornamental Design for a Dial for Timepieces, of which the following is a specification, reference being had to the accompanying drawing, forming part thereof.

The figure is a plan of the dial and hands of the timepiece, showing my new design.

I claim:

The ornamental design for a dial for timepieces, as shown.

GEORGE A. VAIPAN.
